SUCTION CLEANER

Ward Leathers, Haworth, N. J., assignor to The Quadrex Corporation, a corporation of Connecticut

Application July 14, 1931, Serial No. 550,635

12 Claims. (Cl. 15—158)

The object of my invention is to produce, in conjunction with my other inventions in this art represented by co-pending patent applications Nos. 472,703—474,584—476,834—477,831—

5 477,832—481,407—488,793—488,794—489,281—
491,415—492,424—493,068—501,873—501,874—
10 501,875—501,876—501,877—563,507—563,508, a
lightweight vacuum broom for doing the work of
the kitchen broom, the carpet sweeper, and the
dry mop on smooth floors, or for surface pick-up
over rugs and carpets.

In order to accomplish this purpose more efficiently the broom portion of the cleaner requires a highly specialized structure and I have invented 15 means of producing such satisfactory and operable mechanism of a highly flexible sort, the construction of which is set forth in this specification.

In order that a lightweight, surface cleaner for 20 these purposes should be most adaptable and practical in the hands of the operator, I have found the need for mounting the brush and suction nozzle flexibly with respect to a handle-supported motor-suction-filter-unit, in other words with respect to the body-portion of the cleaner. This I have accomplished by means of carrying a removable brush or broom in a stiff transverse support joining the same to the motor-suction unit by flexible spring-like means, and surrounding the whole with a flexible housing.

In order to set forth my invention so that all those familiar with these arts may understand I have prepared the following specification to which I have appended drawings of which—

35 Figure I is a partially sectioned front elevation of the broom and housing assembly complete.

Figure II is a vertical cross-section taken near the end of the nozzle.

Figure III is a vertical cross-section at the center of the nozzle.

Figure IV is a cross-section at the point of support.

Figure V is a partially cross-sectioned front elevation of broom and housing, somewhat modified.

45 Figure VI is a longitudinal cross-section of the same.

In Figure I, a brush or broom back 1 supports bristles 2 of suitable length. This brush or broom is supported in a channel 3 and held, from falling out, by permitting the brush back 1 to extend into the recess 4 in the flexible rubber housing 5. A lip 6 in this housing holds the broom back 1 permitting the removal of the broom by pulling back 55 the rubber portion 7 with the finger. 3 is shown as a stamped part in which outwardly extending louvers as at 8 are provided on both sides. Lugs 9 of rubber as at 8 are provided in the side walls of the housing 5 to fit between the louvers 8. A tubular neck 10 on the housing 5 is joined in

operable manner to the suction inlet (see Figures III, IV and VI). Suitable motor-suction-units and housings are fully described in the co-pending applications above referred to.

Figure II shows a cross-section of the broom mechanism taken at the dotted line AA. The metal supporting member 3 has ends enclosed at the outside ends of brush 2, said ends joined in any suitable manner as by a rivet 11 and tucked away in cavities in the housing 5, at 4. Side 10 wings of the part 3 are turned about the rubber beads in the housing 5 at 12. These wings extend substantially the entire length of the housing. The louvers 8 are so pressed outward from the center that they permit the inflow of air at 15 the bottom where the metal makes a continuous straight edge at 13. The sidewise movement of the bristles in use thereby substantially closes the inlet ports on the rearward side of the broom automatically as it is pushed to and fro.

Figure III shows a cross-section of the broom and housing mechanism taken longitudinally at the center thereof. Here it will be clearly noted that the flexible housing 16 need provide no support for the broom except a latch against its own weight at 6, since the broom channel 3 is supported from the motor-suction-housing 14 by a spring 15 suitably attached at both ends. In the drawings 15 is shown riveted to 3 and held in side slots in the casting 14.

Figure IV more clearly shows the juncture between the flexible rubber housing 5, the motor-suction-housing 14, and the spring 15. A set screw 16 keeps the brush unit from falling out.

Figures V and VI illustrate essentially the same mechanism except for an important modification consisting of the adaptation of a die-casting 21 to these same functions, instead of a stamped sheet metal part. The die-casting make a structure that will stand much rougher use since it is unbendable. The broom 1 and 2 is supported in a slot in the die-casting in a manner similar to that described in Figure I. The openings operated by the louvers 8 are replaced by ports 17, shown plain on the inside 45 and inclined at the upper edge on the outside of the casting as at 18. The air passages between the rubber and the casting are maintained by wings 19 on the die-casting. Lugs 20 on the top of the die-casting 21 aid in holding the spring rigidly supported therebetween as by riveting. The casting 21 projects sidewise at the bottom at 22 furnishing metallic contact with the floor rather than rubber, and furnishing support for the beads on the rubber housing 5. The rubber housing is held in place on the ends by lips 6 which project inwardly under the casting 21 and project a further sufficient distance to engage the ends of the brush, keeping the same 60

from falling out, and providing means for manually removing said brush.

Having set forth my invention in terms which all those familiar with these arts can understand, 5 I wish it understood that many changes in design and detail may be made without departing from the spirit of my invention.

I claim:

1. In combination, a suction-cleaner body-portion; and a mouth piece flexibly communicating therewith; the body-portion being off the floor and the mouth-piece on the floor when the cleaner is in use; and a strip of springy material supporting the body-portion from the mouth-piece and disposed to permit a fore and aft yielding between said parts.

2. In combination, a suction-cleaner body-portion; and a mouth-piece flexibly communicating therewith; the body-portion being off the floor and the mouth-piece on the floor when the cleaner is in use; and a permanently bent strip of springy material supporting the body-portion from the mouth piece and disposed with the convex face of said bent strip facing toward the front of the cleaner.

3. In combination, a suction-cleaner body-portion and an elongated transversely-extending mouth-piece flexibly communicating therewith, the former being off the floor and the latter 30 on the floor when the cleaner is in use; and a strip of springy material connecting the middle part of the mouth-piece with the body portion which latter it supports.

4. In combination, a suction-cleaner body-portion; and a mouth-piece; the former being off the floor and the latter on the floor when the cleaner is in use; a strip of springy material supporting the body-portion from the mouth-piece and disposed to permit a fore and aft yielding between said parts; and a housing made of soft, yielding substantially air-tight material forming a housing for the mouth-piece and the supporting-strip and also serving to connect pneumatically the mouth piece and the body-portion of the cleaner, whereby the housing is 45 adapted to flex conformably with the supporting strip.

5. In combination, a suction-cleaner body-portion; and a mouth-piece; the former being off the floor and the latter on the floor when the cleaner is in use; a permanently bent strip of springy material supporting the body-portion from the mouth piece and disposed with the convex face of said bent strip facing toward the front of the cleaner; and a housing made of soft, yielding substantially air-tight material forming a housing for the mouth-piece and the supporting-strip and also serving to connect pneumatically the mouth piece and the body-portion of the cleaner, whereby the housing is 60 adapted to flex conformably with the supporting strip.

6. In combination, a suction-cleaner body-portion and an elongated transversely-extending mouth-piece, the former being off the floor and the latter on the floor when the cleaner is in use; a strip of springy material connecting the middle part of the mouth-piece with the body portion which latter it supports; and a housing made of soft, yielding substantially air-tight material forming a housing for the mouth-piece and the supporting-strip and also serving to connect pneumatically the mouth piece and the body-portion of the cleaner, whereby the housing is 70

adapted to flex conformably with the supporting strip.

7. In combination, a suction-cleaner body-portion; a mouth-piece; a housing of soft flexible material forming an operative pneumatic connection between the mouth-piece and the body-portion, said mouth piece being recessed within the lower end of said housing; the mouth piece having openings through its sides for the dirt-laden air to pass from the mouth-piece up through the flexible housing into the body-portion of the cleaner; and means which spaces the sides of the mouth-piece from the adjacent walls of the housing and provides for the free passage of the dirt-laden air as aforesaid.

8. A suction-cleaner comprising in combination an inflexible channeled mouth-piece; a housing of soft, flexible substantially air-tight material having a lower-end containing and permanently united to said inflexible channeled mouth-piece; and a brush whose back is seated in the channel of the inflexible channeled mouth-piece with its bristles projecting from the mouth of the channel, the ends of said back projecting beyond the ends of the channel; the soft flexible housing 25 being adjacently recessed to receive said ends of the back of the brush and having lugs which underlie said ends for releasably supporting the brush in the channeled mouth-piece.

9. In combination, a suction-cleaner body-portion; a brush holding mouth-piece comprising a channel-shaped member with brush seated in the channel with its bristles projecting therefrom; a housing of soft flexible substantially air-tight material pneumatically connected with the suction-cleaner body-portion and having an open lower end receiving into it the channeled mouth-piece which latter at its mouth has outwardly extending flanges engaged with the housing, said channel being provided with openings for the 40 dirt-laden air to pass into the flexible housing; and means which supports the body-portion of the cleaner from the mouth-piece.

10. In combination, a suction-cleaner body-portion, a mouth-piece, and a hollow rubber 45 housing operatively supporting the body-portion off the floor with the cleaner resting on the mouth-piece, and forming a twistable and a fore and aft yielding, flexible, pneumatic connection between the mouth-piece and the body-portion.

11. In combination, a suction-cleaner body-portion, a mouth-piece, and a hollow rubber housing operatively supporting the body-portion off the floor with the cleaner resting on the mouth-piece, and forming a twistable and a fore 55 and aft yielding, flexible, pneumatic connection between the mouth-piece and the body-portion, and yielding metal means arranged also to support said body-portion yieldingly from the mouth-piece.

12. In combination, a suction-cleaner body-portion having a tubular intake, a hollow rubber housing, a mouth-piece secured to one end of the rubber housing, the other end of said housing being telescopically connected with the tubular 65 intake of the body portion, and a strip of springy material located within the rubber housing with its lower end fastened to the mouth-piece and with its upper end socketed in the tubular intake of the body-portion for ready 70 attachment and removal along with the rubber housing and the mouth-piece.
